SAFETY KIT FOR SPORTSMEN
Ivan R. Cranston, 1514 S. 4th St. W.,
Missoula, Mont. 59801
Filed May 11, 1967, Ser. No. 637,816
9 Claims. (Cl. 431—291)

ABSTRACT OF THE DISCLOSURE

A safety kit for sportsmen, having a folded sheet of plastic, coiled cord, and a match and candle unit packed in a carrying case. The match and candle unit has a housing with a central compartment containing a candle and a set of surrounding compartments containing matchsticks. An annular closure on the housing covers the surrounding compartments but has an aperture through which matchsticks may be dispensed upon rotation of the closure on the housing. A removable cap covers both the closure and the central compartment. The candle has a combustible jacket with a filler of wax therein, the jacket constituting the sole wick of the candle.

This invention relates to new and useful improvements in safety kits for sportsmen, hunters and other persons who on occasions may become lost or stranded with the possibility of having to survive overnight or longer in the open.

Under such adverse conditions exposure is the greatest source of danger, and the two basic needs for preventing or minimizing exposure are the ability to provide some heat and the ability to derive some shelter from the elements.

The principal object of this invention is to provide a safety kit which includes, among other things, a sheet of plastic material for sheltering purposes, and a match-and-candle combination for purposes of heating. The plastic sheet is brightly colored so that apart from its primary use as a shelter, it may also be used in signalling or marking the lost person's location. Additionally, the plastic sheet may be used for wrapping any game such as may have been caught, the brightly colored sheet thus also serving to attract attention so that the person carrying the game is not accidentally shot by other hunters. Manifestly, apart from its primary purpose in providing heat, the candle may also be used to provide light and for signalling or location marking.

An important feature of the invention resides in the construction of the match-and-candle unit, which includes a housing provided with a central compartment containing the candle and with a plurality of surrounding compartments containing matchsticks, the surrounding compartments having an annular dispensing closure through which the matchsticks may be removed one at a time without the danger of them falling out and becoming lost. The housing also has a removable cap which covers not only the closure of the surrounding compartments but also the candle-containing central compartment, so that both the candle and the matchsticks are safe-guarded against moisture.

Another important feature of the invention resides in the structure of the candle itself, the same consisting of a jacket of combustible material having a wax filler, the combustible jacket constituting the sole wick of the candle.

As already stated, the various components of the kit are compactly packed in a carrying case, from which they may be readily removed for convenient use as required.

The invention is simple in construction, efficient and dependable in use, and lends itself to economical manufacture.

2

These together with other objects and advantages which will become subsequently apparent reside in the details of construction and operation as more fully hereinafter described and claimed, reference being had to the accompanying drawings forming a part hereof, wherein like numerals refer to like parts throughout, and in which:

FIGURE 1 is a perspective view of the safety kit of the invention;

FIGURE 2 is a vertical sectional view on an enlarged scale, taken substantially in the plane of the line 2—2 in FIGURE 1;

FIGURE 3 is a perspective view of the plastic sheet in its unfolded condition;

FIGURE 4 is a perspective view of the coiled cord;

FIGURE 5 is a group perspective view of the match-and-candle unit;

FIGURE 6 is a vertical sectional view thereof on an enlarged scale;

FIGURE 7 is a cross-sectional view, taken substantially in the plane of the line 7—7 in FIGURE 6; and

FIGURE 8 is a perspective view of the candle per se.

Referring now to the accompanying drawings in detail, more particularly to FIGURES 1—4 inclusive, the safety kit for sportsmen is designated generally by the reference character 10 and embodies in its construction a substantially rectangular case 11 which may be formed from leather, plastic, or the like, the case having an openable top or cover 11a releasably held in its closed position, as by suitable fasteners 12. The back wall of the case may be equipped with a loop 13 so that the case may be conveniently carried on the body of the user, as for example, by passing the loop 13 over the user's belt indicated at 14.

The bottom portion of the case 11 contains a folded sheet of plastic material 15 which, in its folded condition, is shown in FIGURE 2 while FIGURE 3 shows the same in an unfolded condition. The plastic sheet 15 may be rectangular and is preferably provided along its marginal edges with reinforced eyelets 16 through which lengths of cord 17 may be passed. Thus, the unfolded sheet 15 may be wrapped around the body of the user for protection against cold or moisture, or alternatively, it may be suspended from suitable overhead supports, such as tree limbs, to serve in the manner of a sheltering wall or tent. In either event, the cords 17 passed through the eyelets 16 may be used to hold the sheet in position and if desired, the cords may be provided at one end thereof with a loop as indicated at 17a in FIGURE 4 to prevent them from being withdrawn from the eyelets 16.

The plastic sheet 15 is preferably brightly colored, as for example, bright red, so that apart from its primary purpose of providing shelter, it may also be used for signalling or marking the location of the stranded person. Additionally, the sheet may be used for wrapping game which has been caught, the brightly colored sheet thus attracting attention so as to prevent the possibility of the person being accidentally shot by other hunters.

In the packed condition of the kit, the sheet 15 is folded and stored in the bottom portion of the carrying case 11 as shown in FIGURE 2, with sufficient room being left in the case above the folded sheet for storage of additional articles, as for example, the cord 17 which may be coiled as indicated in FIGURE 4 and tied to prevent uncoiling, as for example, by a suitable tying element 17b. The coiled cord 17 may be placed in the carrying case 11 on top of the folded sheet 15 and adjacent one side wall of the case, while a combined match and candle unit 18, hereinafter described, may be positioned in the upper portion of the case on top of the folded sheet 15 alongside the coiled cord 17.

Attention is now directed to the match and candle unit 18 which is shown in detail in FIGURES 5—8. The same comprises a substantially cylindrical housing 19 having

an open top and a closed bottom 20, and radially spaced inner and outer side walls 21, 22, respectively, the inner wall 23 defining a central compartment in the housing to accommodate a candle 24. A plurality of radial partitions 25 extend between the inner and outer side walls 21, 22, thus providing a plurality of relatively small outer compartments 26 each accommodating a match stick 27. The match sticks 27 are positioned in the compartments 26 with the match stick heads 27a oriented downwardly so as to rest on the bottom wall 20 and the match sticks are prevented from sliding upwardly or outwardly from the compartments 26 by an annular closure 28 which is rotatably positioned on the upper end of the housing.

The annular closure 28 is of a U-shaped cross-section with inner and outer flanges 28a, 28b telescoped over the respective side walls 21, 22. The outer side wall 22 is formed integrally with an annular rib 29 engaging a complementary groove in the outer flange 28b of the closure 28, whereby to rotatably hold the closure in position.

The upper portion of the closure 28 is formed with an aperture or opening 30 which is selectively registerable with the compartments 26 to facilitate individual and successive dispensing of match sticks from these compartments. The aperture 30 is large enough to permit the match stick 27 to slide freely outwardly when the housing is placed in an inverted position, but the aperture is small enough to prevent passage of the enlarged match stick head 27a, unless the match stick is forcibly withdrawn. In this manner, accidental discharge and possible loss of match sticks will be effectively prevented.

A removable cap 31 is applied to the housing 19 over the closure 28, so as to cover not only the aperture 30 in the closure, but also the central compartment containing the candle 24. In this manner the entire device is rendered substantially water-tight so that access of moisture to the match sticks and to the candle is prevented. A suitable abrasive pad 32 is provided centrally on the underside of the cap 31 so that the matches may be scratched thereon for ignition.

The candle 24 itself is of a unique construction in that it comprises a tubular or cylindrical jacket 33 of combustible material, containing a filler of candle wax 34. The jacket 33 constitutes the sole wick of the candle, and although the jacket burns after being ignited, it still serves to retain the molten candle wax while the burning is in progress. It will be noted that by utilizing the jacket 33 as the wick, the provision of the conventional axial wick at the center of the candle is eliminated. If desired, a combustible tab of laminated paper, or the like, may be secured to the jacket 33 as indicated at 35, so that the candle may be readily ignited by first setting fire to the tab 35, which then sets first to the jacket 33 itself. The use of the kit is further enhanced by the provision of a mirror 36 on the bottom surface of the closed bottom 20 so that signals can be sent by flashing reflected sunlight in a known manner. Also, a compass 37 is provided on the top surface of the removable cap 31 so that a person, such as a hunter, can readily determine his direction of movement.

The foregoing is considered as illustrative only of the principles of the invention. Further, since numerous modifications and changes will readily occur to those skilled in the art, it is not desired to limit the invention to the exact construction and operation shown and described, and accordingly all suitable modifications and equivalents may be resorted to, falling within the scope of the invention as claimed.

What is claimed as new is as follows:

1. In a safety kit for sportsmen, a match-and-candle unit comprising in combination, a substantially cylindrical housing having a bottom, an open top and radially spaced inner and outer side walls, a plurality of radial partitions provided between said side walls and defining therebetween a plurality of relatively small outer compartments

compartments containing matchsticks, the inner side wall defining therewithin a relatively large central compartment circumferentially surrounded by said outer compartments and containing a candle, an annular closure rotatably mounted on said housing and covering the open upper ends of said outer compartments while leaving the top of the central compartment open for access to the candle therein, said closure being provided with an aperture selectively registerable with the outer compartments upon rotation of the closure on said housing whereby matchsticks in the outer compartments may be individually and successively removed through said aperture, and a cap removably superposed on said closure and covering both said aperture and the open top of the central compartment.

2. The device as defined in claim 1 together with means rotatably retaining said closure in position on said housing.

3. The device as defined in claim 1 wherein the matchsticks have enlarged heads resting on the bottom of said outer compartments, said aperture in said closure being large enough to permit a matchstick to slide freely therethrough when said housing is inverted but small enough to prevent passage of the enlarged matchstick head unless the matchstick is forcibly withdrawn.

4. The device as defined in claim 1 wherein said annular closure has an inverted U-shaped cross-section providing a top portion with depending inner and outer flanges, said inner and outer flanges being telescoped over the respective inner and outer side walls of said housing.

5. The device as defined in claim 1 together with a match scratch pad provided centrally at the underside of said cap.

6. The device as defined in claim 1 wherein said candle comprises a jacket of combustible material and a filler of wax in said jacket, said jacket constituting the sole wick of said candle.

7. A container for protected storage for use in a safety kit for sportsmen comprising: a substantially cylindrical housing having a bottom, an open top and radially spaced inner and outer side walls, a plurality of radial partitions provided between said side walls and defining therebetween a plurality of relatively small outer compartments for use in storing matchsticks, the inner side wall thereof defining a relatively large central compartment circumferentially surrounded by said outer compartments and adapted to contain a candle or other fire sustaining device, an annular enclosure rotatably mounted on said housing and covering the open upper end of said outer compartments while leaving the top of the central compartment open for access thereto, said closure being provided with an aperture selectively registerable with the outer compartments upon rotation of the closure on said housing whereby the contents in the outer compartments may be individually and successively removed through said aperture, and a cap removably superposed on said closure covering both said aperture and the open top of the central compartment.

8. The device as defined in claim 7 together with means rotatably retaining said closure in position on said housing.

9. The device as defined in claim 8 wherein said annular closure has an inverted U-shaped cross-section providing a top portion with dependent inner and outer flanges, said inner and outer flanges being telescoped over the respective inner and outer side walls of said housing.
